UNITED STATES PATENT OFFICE.

CHARLES KLENK, OF ENGLEWOOD, NEW JERSEY, ASSIGNOR TO THE PALM BROTHERS COMPANY, OF NEW YORK, N. Y.

DESIGN FOR A PLATE OR SIMILAR ARTICLE.

53,305.

Specification for Design.

Patented May 13, 1919.

Application filed February 21, 1919. Serial No. 278,531. Term of patent 3½ years.

To all whom it may concern:

Be it known that I, CHARLES KLENK, a citizen of the United States, residing at Englewood, in the county of Bergen and State of New Jersey, have invented a new, original, and ornamental Design for a Plate or Similar Article, of which the following is a specification, reference being had to the accompanying drawing, forming part thereof.

The figure is a plan view of a plate showing my new design.

I claim:

The ornamental design for a plate or similar article, as shown.

CHARLES KLENK.

Witnesses:

ALBERT S. BECKER,
ELIZABETH A. HENDERSON.
